UNITED STATES PATENT OFFICE.

CHARLES A. WILBRAHAM, OF POQUONOCK, CONNECTICUT.

FORMER FOR SHEET-METAL VESSELS.

SPECIFICATION forming part of Letters Patent No. 352,019, dated November 2, 1886.

Application filed August 25, 1886. Serial No. 211,830. (No model.)

To all whom it may concern:

Be it known that I, CHARLES A. WILBRAHAM, of Poquonock, in the county of Hartford and State of Connecticut, have invented a new and Improved Former for Sheet-Metal Vessels, of which the following is a full, clear, and exact description.

My invention relates to formers for use in shaping sheet-metal vessels, and has for its object to provide simple, inexpensive, and effective devices of this character, allowing the vessel-bodies to be bent or shaped truly with economy of time and labor.

This invention consists in certain novel features of construction and combinations of parts of the former, all as hereinafter fully described and claimed.

Reference is to be had to the accompanying drawings, forming a part of this specification, in which similar letters of reference indicate corresponding parts in all the figures.

Figure 1 is a plan view of my improved former, partly broken away and in section, and with a wired metal blank adjusted to and bent around the former. Fig. 2 is a vertical sectional elevation taken on the line *x x* in Fig. 1, and shows also a part of a work-bench, to which the former is held; and Figs. 3 and 4 are plan views illustrating the use of the former in making the final bends in the metal blank.

The bed-plate A of the former is provided with a pendent lug or horn, *a*, preferably made square or flat-sided, and which may be set into a recess or socket, *b*, of a work-bench, *B*, to hold the bed-plate immovably to the bench. The bed A is preferably made heart-shaped or with a marginal depression at the front edge, as at *a'*, to allow more convenient operation of a clamp-screw presently described.

To the upper face of the bed A there is fixed a former-block, C, which may be attached by screws, as at *c*, or may be cast or otherwise formed in one piece with the bed-plate. The outer edge portion of the block shown describes a true circle for making half-circular bends of a metal blank around it, and the inner or front margin of the former-block is cut away to produce an edgewise depression, as at *c'*, thereby giving the block a heart or shield shape, as clearly shown in the drawings.

One or more endless metal bands, D, are bent

flatwise to nearly the marginal shape of the former-block C, and are adapted to be set edge-wise on the bed A, around the block C, and against each other, and as few or many of these bands D may be used as the diameter or width of the finished sheet-metal vessel may require.

In the top of the bed-plate A is formed a groove, *e*, in which is fitted to slide a clamp-bar, E, the outer end, *e'*, of which is upturned to serve as a jaw to clamp the blank against the former-block C or a band, D, thereon, and the other end, *e''*, of the bar E is also upturned, and in it is threaded a screw, F, preferably having a crank-handle, *f*, allowing it to be turned in against one of the bands D at the center of the depression of the former-block. The block C has a recess, *c'*, ranging parallel with the clamp-bar E and opening to it, and in this recess a lug or pin, *e''*, on the bar enters; and a spring, G, placed in the recess *c'* and between its forward end and the clamp-bar lug *e''*, acts normally to force the clamp-jaw *e'* away from the gage-bands D on the former-block when the screw F is turned outward.

In using the former, when one or more of the bands D are adjusted on the block C, a sheet or blank, H, of metal, when flat and wired at one edge and marked at the center, is placed between the clamp-jaw *e'* and the outer band D, wired edge down, and with the center-mark at the center of the clamp-jaw. The screw F will then be tightened against the bands D, to draw the bands evenly to the block C and clamp the blank H firmly between the jaw *e'* and the bands, and the blank may then be bent by the hands or otherwise around the bands and block C, to form one truly-curved end or bend, 1, of a finished vessel—a wash-boiler, for instance—and the blank will then be released by turning the screw F the other way, and one of the ends of the blank will next be clamped by the jaw *e'*, and the blank will be turned to give a second bend, 2, to the blank, as shown in Fig. 3, and the other end of the blank will then be clamped by the jaw *e'* and the blank turned to give it the third or final bend, 3, as shown in Fig. 4, and when the blank is released it will have the form of the body of the vessel, the bend 1 making one end of the vessel, and the bends 2 3 together making the other end of the vessel when soldered or otherwise joined. The

bands D may be applied or removed to gage the sizes of the boilers or vessels being formed.

It is obvious that the former would operate were the former-block C and the bands D made 5 round; but in this case the bands would be liable to slip around on the former-block and render the bending operation somewhat uncertain, while with the block cut away at the front and the bands bent into the recess the projections 10 c^3 at each end of the recess prevent turning or slipping of the bands on the block and insure correct bending of the sheet-metal blanks or vessel-bodies, with economy of time and labor as compared with bending the blanks 15 by rolling or other processes.

Having thus described my invention, what I claim as new, and desire to secure by Letters Patent, is—

1. The combination, in a former for sheet-metal vessels, of a bed-plate, a former-block held thereto, one or more gage-bands fitting over said block and each other, and a clamp adapted to hold the blank to the band or bands prior to bending the blank, substantially as 25 shown and described.

2. The combination, in a former for sheet-metal vessels, of a bed-plate, a former-block held thereto and shaped at one part to the required bend of the blank, and formed marginal- 30 ly elsewhere to prevent turning of like-shaped bands placed around the block, and said bands and a clamp adapted to hold the blank to the

block-bands prior to bending the blank, substantially as shown and described.

3. The combination, in a former for sheet-metal vessels, of a bed-plate, a former-block held thereto and shaped at one part of its margin to the required bend of the blank and formed marginally elsewhere with a recess, and like-shaped band or bands placed on the block, 35 and a clamp device adapted to hold the metal blank to the band and press on the recessed or indent portion of the band to simultaneously draw the band or bands tightly around the block to insure a true bend of the blank, substantially as shown and described. 40

4. The combination, in a former for sheet-metal vessels, of a bed-plate, A, grooved at e , a clamp-bar, E, fitted in said groove, a former-block, C, on bed A, and a screw, F, fitted in 45 bar E, substantially as shown and described.

5. The combination, in a former for sheet-metal vessels, of a bed-plate, A, former-block C, one or more gage-bands, D, clamp-bar E, and screw F, substantially as shown and de- 50 scribed.

6. The combination, in a former for sheet-metal vessels, of a bed-plate, A, former-block C, clamp-bar E, screw F, and a spring, G, substantially as shown and described.

CHARLES A. WILBRAHAM.
